CLAIM

The ornamental design of a panel hook, as shown and described.

DESCRIPTION

FIG. 1 is a side elevational view of a panel hook in accordance with the present invention;

FIG. 2 is a front elevational view of the panel hook of FIG. 1;
FIG. 3 is a rear elevational view of the panel hook of FIG. 1;
FIG. 4 is a top plan view of the panel hook of FIG. 1; and,
FIG. 5 is bottom plan view of the panel hook of FIG. 1.

The broken line showing of portions of the panel hook is included for the purpose of illustrating environment and forms no part of the claimed design.

1 Claim, 2 Drawing Sheets

FIG. 3

FIG. 4

FIG. 5
